(57) **CLAIM**

The ornamental design for a lid and container assembly, as shown and described.

DESCRIPTION

FIG. 1 is a top perspective view of a first embodiment of a lid and container assembly according to our new design.

FIG. 2 is a bottom perspective view of the lid and container assembly of FIG. 1.

FIG. 3 is a left side view of the lid and container assembly of FIG. 1.

FIG. 4 is a rear view of the lid and container assembly of FIG. 1.

FIG. 5 is a right side view of the lid and container assembly of FIG. 1.

FIG. 6 is a front view of the lid and container assembly of FIG. 1.

FIG. 7 is a top view of the lid and container assembly of FIG. 1.

FIG. 8 is a bottom view of the lid and container assembly of FIG. 1.

FIG. 9 is an exploded top perspective view of the lid and container assembly of FIG. 1.

FIG. 10 is a top perspective view of a second embodiment of a lid and container assembly according to our new design.

FIG. 11 is a bottom perspective view of the lid and container assembly of FIG. 10.

FIG. 12 is a left side view of the lid and container assembly of FIG. 10.

FIG. 13 is a rear view of the lid and container assembly of FIG. 10.

FIG. 14 is a right side view of the lid and container assembly of FIG. 10.

FIG. 15 is a front view of the lid and container assembly of FIG. 10.

FIG. 16 is a top view of the lid and container assembly of FIG. 10.

FIG. 17 is a bottom view of the lid and container assembly of FIG. 10; and,

FIG. 18 is an exploded top perspective view of the lid and container assembly of FIG. 10.

The broken lines illustrate portions of the lid and container assembly which form no part of the claimed design.
